UNITED STATES PATENT OFFICE

SIDNEY YANKAUER, OF FLUSHING, NEW YORK

PIPE LIGHTER

Application filed June 24, 1929. Serial No. 373,218.

My invention relates to electrical devices used for lighting tobacco, especially when the tobacco is contained in pipes, although the device may obviously be used to light 5 cigars, cigarettes or the like. Such devices may be attached to the end of a flexible cord to provide a wide field or scope of applicability. The device finds particular application as an automotive vehicle accessory or 10 smoking room convenience comprising the electric unit of the glowing wire type which may be pulled from a socket on the dashboard or in the wall in a manner well known in the art by means of a flexible automatically 15 retractable cord extension.

The object of the invention is to provide an electric lighter of a novel construction facilitating the introduction of its glow body into the bowl of a pipe and adapted to effect 20 tively ignite the tobacco therein.

The prior devices which have been designed with the idea of effectively applying an ignition body to the tobacco in pipes so as to ignite the same have been found to 25 fail of their purpose. While it has been recognized that the solution lay in providing the necessary quantity of air to support the combustion of the tobacco and such air has been sought to be introduced into the bowl 30 by means of apertures in the ignition device casing, the mere provision of such apertures as a means of supplying air to the glow body has been found insufficient. I have found that it is necessary, and I have devised an 35 apparatus for attaining that end, to provide a passageway in the lighter casing in communication with the atmosphere such as to cause the ignition air to impinge on the glow body as a column. This column of air is, by 40 the suction through the pipe stem, forced against the blow body and drawn through the mass of tobacco in the pipe bowl providing a free circulation of ignition air. By making 45 the exterior dimensions of the lighter casing somewhat smaller than the average bore of a pipe bowl, I make it possible for the ignition body and therefore the condensed column of air impinging thereon, to be passed 50 over different portions of the tobacco in the

manner of a match and its flame being played over the surface of the bowl opening.

In the accompanying drawings, forming a part of the specification, and in which similar reference characters designate similar parts in the several views, Fig. 1 is a view in elevation of one embodiment of my invention illustrating the application of my new device to a pipe shown in outline; Fig. 2 is a view partly in elevation and partly in section, showing the interior of the igniter portion of the device; Fig. 3 is a section on the line 3—3 of Fig. 2; Fig. 4 is a section on the line 4—4 of Fig. 2; Fig. 5 is a partially sectional elevation of a modification of my improved device; and Fig. 6 is an elevation, partly in section, of still another embodiment of my invention.

Referring more particularly to Figs. 1 to 4 of the drawings, the device comprises a handle member 10 to one end of which is attached a casing in the form of an elbow 11 and to the other, a cap or housing 12 (Fig. 1) which may contain a switch (not shown) controlling the current supplied by conductor wires 13, 14 of the insulated cable 15. Switch button 16 is shown in Fig. 1 as protruding from the metal cap 12. The switch within said cap or housing is accessible for repairs by the removal of the lighter from the housing, (which may form the permanent socket on the dashboard of an automobile or other wall structure to which the device is attachable), by turning the handle 10 axially so as to disengage pin 17 from its position illustrated, into the slot 18 whence it may be withdrawn by a pull of the handle 10. The switch, of course, may obviously be placed on the dashboard or other wall structure at any position from the lighter, the socket construction herein described being only a suggested form thought expedient.

The elbow 11, which may be formed of any suitable material, has attached to its lower portion a tubular projection 19 of some heat resisting and dielectric material. This projection, containing the heating element 20 at its lower extremity, is of such diameter and configuration as to permit of its insertion into the bowl of a pipe 21^a. This projection should

also be of a length sufficient to bring the bottom thereof, and hence the heating element 20, into contact with the tobacco within the bowl no matter how small the amount of such 5 tobacco within the bowl.

The heating or glow element 20 comprises a series of loops of a thin and highly resistant wire embedded in the heat resisting material of projection 19 and having its terminals joined to conductor wires 13 and 14 which are led from the cable 15, through housing 12, handle 10, elbow 11, to the heating end of projection 19. As illustrated in Fig. 4, the glow element is formed in a series 10 of parallel loops embedded in the dielectric substance of member 19 so as to present a heating surface capable of setting fire to the tobacco with which they come into contact.

In order that the tobacco in the pipe may 20 be effectively ignited it is necessary that a free supply of air to support combustion be available. To provide a means of circulation for such air through the tightly packed tobacco and igniting device I construct my new 25 device with a free passage opening to the air at a distance from the glow member. In the embodiment illustrated in Figs. 1 to 4, I provide an aperture 21 in the top of elbow 11 through which the passage of the tubular 30 member communicates with the atmosphere. Air is thus sucked through this aperture, drawn in the form of a column through the inner passage of member 19 and through the bottom opening of said member out 35 through the pipe stem. It will be obvious, of course, that the passage may have its aperture 21 anywhere in the member 19 so long as it is a sufficient distance from the glow member to cause the ignition air to impinge on the 40 glow body only after it has been formed into a flowing column as distinguished from a locally swirling mass.

In Fig. 5, I have illustrated a modified form 45 of my new device. It differs from the embodiment hereinabove described in that its metal casing 22 to which is attached the heat resisting projection 23 corresponding to the member 19 of the form first described, is of cylindrical form instead of an elbow. The 50 apertures 24 correspond in their function to the aperture 21 of Figs. 1 and 2. These apertures are located at a distance from the heating end of member 23 sufficient to bring them outside the bowl of the pipe when the device 55 is inserted therein. The apertures 21 and 22, so long as they are free of the pipe bowl, and in contact with the free atmosphere, will suffice to provide the free circulation of air in the manner hereinabove described necessary 60 for a speedy and efficient ignition of the tobacco within the pipe. It is obvious that any number of such apertures 21 and 24 may be provided in the surfaces of the casing members 11 and 22.

65 In Fig. 6 I have illustrated a still further

embodiment of my invention. The device there shown comprises a metal casing 25 having attached thereto tubular section 26 of a non-inflammable material and thermally and electrically insulated from said casing. 70 The glow element 20, located at the end of said tubular section, has one of its conductor wires 27 supplying current thereto connected to the casing 25. The second conductor wire 28 is led through the central passage of tubular member 26, through the metal casing insulated therefrom by the portion of member 26 projecting into the interior of the casing as shown at 30, to its terminal in cap 29.

The tubular section 26 is of such dimensions that its exterior diameter is somewhat smaller than the average bore of a pipe in order that the section may have a freedom of movement when inserted into the bowl of a pipe, to permit of the glow body, and therefore the heat emanating therefrom, being played over the surface of the tobacco in a manner similar to the movement of the flame of a match over the surface of the tobacco within the bowl when the match is passed and repassed over the bowl opening. Furthermore, the small diameter of the tubular section adapts the device to use with any size pipe without restriction by its bore. As in the embodiments hereinbefore described, the length of the tubular member 26 should be such that the device may be used to light a partly filled pipe.

In all of the embodiments illustrated it is 100 obvious that the handle supporting the elbow in one instance, and the tubular sections in the others, should be located as nearly beyond the sphere of heat radiation of the glow body as possible.

I claim:

1. An electrical ignition device comprising a handle, a casing a projecting head of a heat resisting material attached thereto adapted to enter the bowl of a tobacco smoking pipe and having an inner passage from the bottom to at least a point near the top thereof, a heating element in said head comprising a plurality of wire loops embedded in the heat resisting material of said head and having their extremities outwardly exposed therefrom, and electrical conductors in said head and casing in engagement with the ends of said heating element, said inner passage being in communication with the atmosphere by means of an aperture in said casing. 110

2. An electrical ignition device comprising a handle, a casing, a projecting head of a heat-resisting material attached thereto adapted to enter the bowl of a tobacco smoking pipe and having an inner passage from the bottom to at least a point near the top thereof, a heating element mounted across the open bottom end of said head and comprising a plurality of wire loops bent around 120 portions of and anchored in said bottom end 125

of said head, the active portions of said heating element which are in contact with the tobacco in the pipe lying in the direct path of air drawn through the said passage, where-
5 by the air current impinges against the rear surface of said portions of the heating element and then flows through the tobacco, and electrical conductors in said head and casing in engagement with the ends of said heating
10 element, said inner passage being in communication with the atmosphere by means of an aperture in said casing.

3. An electrical ignition device comprising a handle, a casing, a projecting head of a
15 heat-resisting material attached thereto and having an outer reduced portion lying within the casing and also a portion free from the casing adapted to enter the bowl of the tobacco smoking pipe, the exterior contour of the
20 casing and of that portion of the head which is free from the casing having substantially the same cross-sectional dimensions, said head having an inner passage from the bottom to at least a point near the top thereof, a heating
25 element mounted across the open bottom end of said head and comprising a plurality of wire loops bent around portions of and anchored in said bottom end of said head, the active portions of said heating element which
30 are in contact with the tobacco in the pipe lying in the direct path of air drawn through the said passage, whereby the air current impinges against the rear surface of said portions of the heating element and then flows
35 through the tobacco, and electrical conductors in said head and casing in engagement with the ends of said heating element, said inner passage being in communication with the atmosphere by means of an aperture in said
40 casing.
